UNITED STATES PATENT OFFICE.

CONRAD LUTTROPP, OF STOCKHOLM, SWEDEN, ASSIGNOR OF ONE-HALF TO ANDERS LINDAHL, OF STOCKHOLM, SWEDEN.

CALCULATING MACHINE.

Application filed December 10, 1926, Serial No. 153,898, and in Sweden November 6, 1925.

This invention relates to calculating machines of the type having a traveling carriage movable step by step in response to the depression of a key.

5 The object of this invention is to provide simple and reliable means, whereby the carriage may be shifted in either direction and at the same time positively prevented from moving more than one step at each depression no matter how heavy the operation of the key may be.

10 The invention is characterized, chiefly, by the provision on the carriage of a longitudinal ratchet bar having two series of ratchet teeth, one for each direction of movement, one feed dog and one stop dog being provided to cooperate with each of said series of teeth, each such pair of dogs being carried by a separate slide movable towards and

20 away from said ratchet bar under the control of a key while being prevented from moving in a direction parallel to said bar.

15 In the drawing one embodiment of the invention is illustrated. Fig. 1 is a front view of the carriage moving device according to the invention. Fig. 2 is a side elevation of part of the calculating machine. Fig. 3 is a front view of certain parts of the device shown in Fig. 1, in the position said 25 parts occupy at the end of a movement of the ratchet bar to the left. Fig. 4 is a horizontal section taken along the line 4—4 in Fig. 1.

30 The invention is illustrated as applied to a calculating machine the key-board of which comprises ten digit keys.

In Fig. 2 the key-board is indicated at 1 and two keys thereof are shown by dotted lines at 2, 2. Those parts of the calculating 35 machine not required for the understanding of this invention are omitted from the drawing.

The traveling carriage 3 is slidably mounted on stationary tracks 4, 4, preferably by 40 means of balls 5, 5. Attached to the lower portion of the carriage is a ratchet bar 6 having on its under side two series of oppositely directed ratchet teeth 7, 8, respectively. Pivoted to the ratchet bar 6 is a locking lever 50 9, adapted to engage slots 10 formed in a stationary locking bar 11. The spacing of the slots 10 corresponds to the spacing of the teeth of the ratchet bar 6 said last men-

tioned spacing corresponding, in turn, to the 55 spacing of the figure disks of the carriage. The locking lever 9 is provided with a handle 12 to permit manual release thereof, if desired.

55 Situated below the ratchet bar 6 is a stationary guide-block 13 forming vertical guide-ways for two slides 14, 15. Each of said slides is provided with a depending arm 16, 17, respectively, pivoted to one arm of individual bell crank levers of which that 60 associated with the slide 14 is shown at 18 in Fig. 2. The other arm of said lever 18 is connected by a link 19 to one arm of a bell crank lever 21 mounted at 20 and having its other arm connected to a key 22, as shown in 65 Fig. 2. There are, of course, two such connections and keys, one for each of the slides 14, 15.

70 The bell crank lever 18 is formed with an elongated slot 23 guided by the stationary pin 24. Said pin 24 also engages a corresponding slot in the lower portion of a link 25 having a pin 26 engaging a cam shaped portion 27 of the bell crank lever 18. The upper end of the link 25 is pivoted to one 75 arm of a bell crank lever 28 carrying a bridge 30 in engagement with the locking lever 9. The other arm of the bell crank lever 28 is formed as a journal pin 31 engaging the bifurcated shorter arm of a bell crank lever 80 32 the longer arm of which is formed with a stop shoulder 33 to engage a tooth 34 on the main shaft 35 of the calculating machine.

85 Pivoted to the slide 14 by means of a pin 36, see also Fig. 3, is a feed dog 37 adapted 90 to cooperate with the series of teeth 7 of the ratchet bar 6. A spring 38 attached to the rear end of the feed dog 37 tends to move said end downwardly. The slide 14 together with the side walls of the guide-block 13 95 and one end wall 39 thereof form a vertical guide-way for a stop dog 40 adapted to engage the series of teeth 8 of the ratchet bar 6. By means of a pin 41 attached to the stop dog 40 which engages an elongated slot 100 42 in the feed dog 37 intermediate between its ends the stop dog 40 is pivotally connected to the feed dog 37 without interfering with the desired movement of the feed dog. The feed dog 37 is provided with a lateral 105 projection 43 to engage the stop dog 40 in order to limit the movement of the feed dog

towards the stop dog as caused by the associated parts will be operated similarly as described above.

The slide 15 and its associated parts are equivalent to those described above in connection with slide 14. The slide 15, thus, carries a feed dog 47 adapted to cooperate with the series of teeth 8 and a stop dog 50 adapted to cooperate with the series of teeth 7 of the ratchet bar 6.

10 The operation of the mechanism described is as follows:

Assuming it is intended to move the carriage to the left, the key 22 is depressed thereby causing the bell crank lever 18 to lift both the link 25 and the slide 14. The link 25 causes the bell crank lever 28 to turn on its pivot. As a result, the bridge 30 will lift the locking lever 9 out of engagement with the slots 10 of the locking bar 11, and 15 the journal shaped end 31 of the lever 28 will at the same time move the lever 32 to bring its shoulder 33 into engagement with the tooth 34 thereby temporarily locking the main shaft 35 against rotation. Prior to 20 the above described movement the slide 14 was in the position shown in Fig. 1 in which the dogs 37 and 40 were in released state. By means of the pin 36 the slide 14 in its upward movement moves the feed dog 37 25 upwardly while the spring 38 maintains the feed dog in contact with the stop dog 40. The stop dog is caused by the pin 41 to also move upwardly with the slide. When the 30 point of the feed dog 37 reaches the bottom 35 of that space of the series of teeth 7 which is situated just above the dog any further parallel movement of the feed dog is prevented and, during the continued upward movement of the slide 14, the feed dog is 35 caused to turn on the pin 36 thereby causing the point of the feed dog to move the ratchet bar 6 to the left. As long as this 40 movement continues the stop dog 40 continues its upward movement. The stop dog 45 which was initially on a height below that of the feed dog, as shown in Fig. 1, will in the last portion of the movement enter a space of the series of teeth 8 and will be in full engagement therewith when the feed 50 dog 37 has moved the ratchet bar a distance of one tooth-space to the left. The various parts will now be in the position shown in Fig. 3.

Upon the subsequent release of the key 22 55 the slide 14 will restore to normal moving both of the dogs 37 and 40 out of engagement with the rows of teeth 7 and 8. At the same time the locking lever 9 will enter one of the slots 10 of the locking bar 11 to 60 maintain the carriage in its displaced position. Furthermore, release of the main shaft 35 will be effected simultaneously.

If it is desired to move the carriage to the right the key associated with slide 15 65 is depressed whereby the slide 15 with its

As all of the dogs are normally out of engagement with the ratchet bar 6, as shown in Fig. 1, the carriage may be released by 70 manual depression of the handle 12 of the locking lever 9, whereupon the carriage may be freely shifted in either direction any number of steps desired.

What I claim is:

1. In a calculating machine, a frame, a carriage movable on said frame, a ratchet bar on said carriage having two series of oppositely directed teeth, one feed dog and one stop dog to cooperate with each series 80 of teeth, a separate slide for each pair of dogs movable towards and away from said ratchet bar, and a key to control the movement of each of said slides.

2. In a calculating machine, a frame, a carriage movable on said frame, a ratchet bar on said carriage having two series of oppositely positioned teeth, stationary guiding means, slides in said guiding means movable towards and away from said ratchet bar, a feed dog pivoted to each of said slides, a stop dog movably connected to each of said feed dogs, the feed dog being adapted to cooperate with one of said series of teeth and the associated stop dog being 90 adapted to cooperate with the other series of teeth and means to control said slides.

3. In a calculating machine, a frame, a carriage movable on said frame, a ratchet bar on said carriage having two series of oppositely directed teeth, two slides movable towards and away from said ratchet bar, a feed dog pivoted to each of said slides at its rear end so as to normally occupy an inclined position relatively to the ratchet bar, 100 a stop dog on each slide, and means to control said slides.

4. In a calculating machine, a frame, a carriage movable on said frame, a ratchet bar on said carriage having two series of 110 oppositely positioned teeth, two slides movable towards and away from said ratchet bar, stationary guiding means for said slides, separate controlling means for said slides, a feed dog pivoted to each slide so as to normally occupy an inclined position relatively to the ratchet bar, a stop dog on each slide controlled by said slide and said feed dog in conjunction in such a way as to cause the stop dog to engage the ratchet bar during the last portion of the operation of the feed dog.

5. In a calculating machine, a frame, a carriage movable on said frame, a ratchet bar on said carriage having two series of 125 oppositely positioned teeth, two slides movable towards and away from said ratchet bar, stationary guiding means for said slides, separate controlling means for said slides, a feed dog pivoted to each slide so 130

as to normally occupy on inclined position relatively to the ratchet bar, a stop dog on each slide controlled by said slide and said feed dog in conjunction in such a way as 5 to cause the stop dog to engage the ratchet bar during the last portion of the operation of the feed dog, and a spring acting on said feed dog to maintain its inclined position until the feed dog comes into engagement with the ratchet bar. ¹⁰
In testimony whereof I have signed my name.

CONRAD LUTTROPP.
